DESIGN FOR A DOLL

Ollie Mae Jay, San Antonio, Tex.

Application December 1, 1939, Serial No. 88,615

Term of patent 14 years

To all whom it may concern:

Be it known that I, Ollie Mae Jay, a citizen of the United States and a resident of San Antonio, in the county of Bexar and State of Texas, have invented the new, original, and ornamental Design for Dolls, of which the following is a specification, reference being had to the accompanying drawing, forming part thereof, in which:

I claim:

The ornamental design for a doll, as shown.

OLLIE MAE JAY.
